UNITED STATES PATENT OFFICE.

CLARENCE P. FOLSOM, OF DAYTON, OHIO.

ROLL FOR BEATING-ENGINES.

1,245,577.

Specification of Letters Patent.

Patented Nov. 6, 1917.

Application filed August 2, 1917. Serial No. 184,126.

To all whom it may concern:

Be it known that CLARENCE P. FOLSOM, a citizen of the United States, residing at Dayton, in the county of Montgomery and State of Ohio, has invented certain new and useful Improvements in Rolls for Beating-Engines, of which the following is a specification.

This invention relates to improvements in rolls for beating engines and more particularly to the means for fastening the fly-bars in position so that they are held securely in the roll and may be conveniently and expeditiously removed and replaced when necessity requires. It will be understood that such rolls are employed for beating stock or pulp in the paper-making art, and that owing to such usage the fly-bars are called upon to withstand a very considerable amount of stress or strain and have, therefore, to be securely held in position against any vibration or looseness in the operation of the engine. Owing to the requirement of rigidity in their mounting and the facility with which they may be removed and replaced when occasion requires it is the object of the present invention to provide securing means of a substantial character in the form of specially constructed supporting rings or frames more particularly the means for securing the fly-bars therein, as will hereinafter more clearly appear from the description to follow and the accompanying drawings.

Referring in general terms to the accompanying drawings, Figure 1 represents a vertical sectional view of a beating-engine roll embodying my improvements. Fig. 2 is a somewhat enlarged fragmentary view of the periphery or ring of one of the supporting frames partly in section, showing the fly-bars in position therein. Fig. 3 is a view on the line 3—3 of Fig. 2 showing the periphery or ring of one of the supporting frames partly in section and the fly-bars in cross section. Fig. 4 is a sectional view on the line 4—4 of Fig. 2 and Fig. 5 is a detail elevation of a portion of the periphery or ring of a supporting frame, showing the inner side thereof.

In the more particular description to follow, like reference characters indicate similar parts throughout the description and drawings.

The beater roll comprises a series of spiders or supporting frames 1 which are as-

sembled in proper relative position on shaft 2 and made fast thereon. The periphery or marginal ring of each spider or frame 1 consists of a ring 3, the base of which extends laterally as at 4. The ring 3 of each spider or frame is provided with slots or openings 5 at uniform distances throughout the ring for the reception of the fly-bars 6 which snugly fit therein. The fly-bar 65 openings 5 on the two end spiders or frames do not extend through the periphery or ring portion 3 because the ends of the fly-bars 6 terminate at these two end spiders. There is therefore a shoulder 7 formed at the inner end of each of the openings 5 of end spiders or frames against which the ends 70 of the fly-bars abut. The width of each opening 5 is sufficient to snugly receive the inserted portions of the fly-bars. The fly-bars, it will be seen, taper on one side longitudinally while the other side is straight and the walls of the openings 5 are similarly shaped to receive them. This construction of the fly-bars gives them a wedge-like fit in the openings 5 which is largely depended upon to hold them firmly in position. The openings 5 being of a width to snugly receive the inserted portions of said fly-bars there is thus provided solid walls of 80 hard metal between which the fly-bars are held. This provision prevents the fly-bars from having any looseness or vibration. At an intermediate point in the depth of the openings 5 there are provided on each side 90 recesses 8 which extend farther into the walls of the openings 5. These recesses 8 open out on one side of the ring 3 and terminate in inner abutments or shoulders 9, as seen in Fig. 4. The said recesses 8 receive 95 pins 10 which pass through horizontal and oblong openings 11 in the fly-bars—the portions of the fly-bars lying within the openings 5. As shown in the drawings the pins 10 pass through the openings in the fly-bars 100 and lie across the openings 5, with their ends in the recesses 8. It will be observed that the openings 11 in the fly-bars are of a length to extend inwardly beyond the inner side of the ring 3; therefore the pins 105 110 may be inserted in the recesses 8 by passing them in through the exposed end of openings 11 as seen in Fig. 4 and thence into said recesses. This provision enables the openings 11 to be extended between the walls 115 in the ring 3 below the outer circumferential surface of the ring 3 so that there may be

an upper shoulder 8' which locks the pins 10 from any outward movement. The object and purpose of the pins 10 is to contribute to holding the fly-bars in position against any outward movement due to centrifugal force. When the pins 10 are placed in position they are secured by a surrounding body of metal 12 of a character which has a low-melting point such for example as lead or Babbitt metal. This metal in melted form is poured into the recesses 8 to fill the space around the pins 10 to the outer terminal of said recesses and to fill the openings 11 in the fly-bars. 10 The molten metal is poured into the recesses 8 through openings 13 in a block 14. The block as shown in Fig. 2 is held against the inner side of the ring 3 between two fly-bars. The opening 13 in said block 15 communicates with the inner or exposed end of the opening 11 in the fly-bar and through this opening 13 the metal is poured through said opening 11 and into the recess 8 around the pin. A similar block 15 is 20 placed in a position on the other side of the adjacent fly-bar. This block 15 has no opening 13, its purpose being to block up the other side of the fly-bar opening 11 while the metal is being poured through the opening 13. The blocks 14 and 15, it will be understood, are utilized only to pour the melted metal. After this operation is done they are removed. The metal 12 may be remelted and removed from said recesses 30 by applying a torch thereto and turning the supporting frame 1 to bring each opening 16 in a vertical position for the melted metal to drain out of the recesses 8. The openings 16 are relatively small openings that extend into the ring 3 on one side of the fly-bar at a right angle to the recesses 8, and they communicate with the recesses 8, and when the metal is removed and the pin 10 is free to be displaced, a small tool or 40 implement may be inserted through the opening 16 and the pin pushed out. The openings 17 in the ring 3 at the base of the openings 5 are for convenience in machining the openings 5. They enable the planer or other tool used in machining the openings 5 to be easily removed. Between the fly-bars and running parallel therewith it is customary to provide wooden bars or fillers which expand and become rigid in 50 their positions and contribute in securely maintaining the fly-bars in position. In Fig. 3, 18 designates one of such wood fillers which is thought to be sufficient illustration of these parts owing to their well-known 60 utility.

From Fig. 3 it will be readily seen that the fly-bars are in direct contact with hard metal, to wit, the side walls of the openings 5 and at no point is the softer metal required to withstand the strain exerted on

said fly-bars. The softer metal is required only for locking the pins 10 in their position. The openings in the fly-bars are made oblong so that the softer metal may be poured in the recess 8 and thus avoid increasing 70 the openings 5.

Having described my invention, I claim:

1. In a roll of the character specified, a series of frames terminating in annular rings having radial openings therein from 75 the sides of which extend recesses which lie inwardly from the outer margins of said openings, a series of fly-bars mounted in said radial openings and filling the spaces thereof, said fly-bars having oblong openings 80 therein portions of which lie within said radial openings and register with said recesses, pins penetrating the openings in the fly-bars and the ends of which extend into said recesses, the space surrounding the pins 85 in said recesses, and the openings in the fly-bars being filled with a relatively softer metal whereby the pins are secured in their positions.

2. In a roll for beating engines, a series 90 of frames terminating in rings having transverse openings therein and recesses extending laterally from the walls of said openings at points lying inwardly from the outer margins of said openings, a series of 95 fly-bars projected into the openings in said rings and filling the space thereof, said fly-bars having oblong openings therein portions of which register with said recesses, and other portions of which extend beyond 100 the rings, transverse pins penetrating the openings in the fly-bars and the recesses in the side walls of the ring openings, a filling of softer metal surrounding said pins and filling said recesses and the openings in the 105 fly-bars, and means for pouring said softer metal in a molten state into said recesses and fly-bar openings through the exposed ends of the fly-bar openings.

3. In a roll for a beating engine, a series 110 of frames terminating in marginal rings with horizontal openings therein extending through sides of said rings, transverse recesses in the walls of said ring openings lying inwardly from the outer terminals of 115 said openings, said recesses extending horizontally into the sides of said rings, a series of fly-bars having horizontal elongated openings therein, said fly-bars being inserted in the openings in the rings and completely 120 filling the space of said openings, the horizontal elongated openings in the fly-bars registering with the recesses in the walls of the ring openings, a series of pins penetrating the openings in the fly-bars and the ends 125 of which lie within the recesses in the walls of said ring openings, a filling of relatively soft metal closing the space surrounding said pins within said recesses and closing the openings in the fly-bars, and means for 130

pouring said metal into said recesses and openings through the exposed portions of the openings in the fly-bars.

through the openings extending from the outer peripheries of the rings into one of the recesses extending from said ring openings.

35

5. A roll for beating engines comprising a series of frames terminating in rings having horizontal openings therein extending through the outer peripheries of said rings and lateral recesses extending into the walls of said openings at points inwardly from the outer terminals of said openings, and openings extending from the outer peripheries of said rings into one of the recesses extending from each ring opening, a series of fly-bars having oblong horizontal 10 openings therein, said fly-bars being inserted into the openings in said rings and filling the space of said openings, a portion of the openings of the fly-bars being in register with the recesses in the walls of the 15 ring openings, and a portion of said openings in the fly-bars being exposed, a series of pins within the inner portions of said fly-bar openings and the ends of which lie within the recesses in the walls of said ring 20 openings, a soft metal filling surrounding the pins within said recesses and filling said recesses and the openings in said fly-bars, said filling being introduced through the exposed portions of the openings in the 25 fly-bars in melted form, said filling being adapted to be remelted and discharged 30
